FIG. 1 is a perspective illustration showing my new design for a device for internally photographing pipe;

FIG. 2 is a front end elevational view thereof;

FIG. 3 is a rear end elevational view thereof;

FIG. 4 is a top plan view thereof;

FIG. 5 is a side elevational view thereof, the opposite side being a mirror image of the side shown; and

FIG. 6 is a bottom plan view thereof.

I claim:

The ornamental design for a device for internally photographing pipe, as shown and described.
